MODULATION

Lothar Brück, Berlin, Germany, assignor to Tele-funken Gesellschaft für Drahtlose Telegraphie, Berlin, Zehlendorf, Germany, a corporation of Germany

Application March 4, 1941, Serial No. 381,624
In Germany November 8, 1939

3 Claims. (Cl. 179—171.5)

This application concerns a modulation circuit organization for radio-frequency transmitters comprising a rectifier. The present invention is an improvement of the system disclosed in Brück's application #336,546 filed May 22, 1940 now United States Patent No. 2,269,140, dated January 6, 1942.

A modulation circuit arrangement for radio-frequency transmitters has been disclosed in the said Brück application which follows a straight-line law up to very high modulation percentages. The disclosure of the said application is predicated upon a modulation scheme known in the prior art in which a rectifier, for example, a diode, is connected in series with a load resistance and the series combination connected to an oscillatory circuit included in the plate circuit of a tube, the modulation potential being impressed upon the said load resistance. The invention of the above mentioned application essentially is that (1) the modulation voltage is fed to the rectifier load resistance, which is bridged or shunted for radio frequency by a condenser, or else is fed to a transformer winding connected in series to the resistance. (2) The said ohmic load resistance is made of such dimension that the characteristic of the rectifier, direct current as a function of the direct-current potential for various radio-frequency potentials fed to the preceding tube, is covered by the modulating audio frequency as symmetrically as possible. (3) The modulated radio-frequency potential is taken off from the oscillation circuit which is included in the plate circuit of the tube having a high internal resistance.

Now, the present invention is concerned with the problem to stabilize the modulation percentage, in a circuit arrangement of the kind disclosed in the said Brück application, in spite of variations of the operating potentials, that is to say, the direct-current voltages. It will be remembered that such fluctuations of the working voltage, in the first place, cause a change in the radio-frequency amplitude, and, in the presence of unvaried modulation potential a change in the percentage of modulation, and this is undesirable, for instance, in work with measuring transmitters.

According to the invention, to the end of insuring stabilization of the modulation percentage, independently of the variations of the working voltage, the load resistance is additionally subjected to a direct-current voltage which is obtained by rectification of the modulation fre-

quency in a second rectifier and second load resistance.

Figs. 1 and 2 illustrate exemplified embodiments of my improved modulation system and Fig. 3 illustrates by graphs practical results of the invention.

Referring to Fig. 1, the amplifier tube V, the same as in the parent application, is fed with the unmodulated radio-frequency potential UHF. The carrier is amplified in tube V and supplied to the secondary winding S of a transformer T and thence to output means. The diode 1 has two electrodes 6 and 10 connected in shunt to the tuned circuit Sch. Rectification in the diode 1 sets up current in the load resistance R1. Now, this load resistance R1, through the transformer T1, is fed with the modulation frequency UNF from a source 12. The modulated radio-frequency potential is as stated above taken from the oscillation circuit Sch.

To stabilize the modulation percentage irrespective and independently of fluctuations in the working voltage, according to an object of the invention, a second rectifier 2 having electrodes 14 and 18 connected with load resistance R2 is provided. This rectifier 2 is fed with the audio frequency by way of the transformer T2. The condenser C2 serves for audio-frequency bridging or by-passing of the resistance R2, while the condenser C1 serves for the radio-frequency by-passing of the resistance R1. The direct-current voltage which is set up across the resistance R2 as a result of the rectification of the audio frequency is applied by way of the wire 18 to the left hand end of the resistance R1. The circuit is so balanced that in the presence of normal or rated working voltages the direct-current voltages across resistance R1 and R2 are of like size, with the result that no direct current flows through the wire 18.

But, if, for some reason or other, the audio-frequency potential or the radio-frequency potential changes, then a direct current will flow through the wire 18. According to its direction this direct current will either act in a damping or a boosting manner upon the radio-frequency circuit. As a consequence, the radio-frequency amplitude is always maintained at a certain ratio to the audio-frequency amplitude so that the modulation percentage is approximately stabilized.

Suppose the audio-frequency potential is constant, while the radio-frequency potential diminishes. As a result, the direct-current poten-

tial across R_1 diminishes below the value of that acting across resistance R_2 . The further result is that a current will be caused to flow through wire 18 tending to equalize the two potentials. The said direct current acts the very same way as if the left hand diode were impressed with a negative biasing potential. As a result, the damping effect produced by the diode upon the radio-frequency circuit is lessened and the radio-frequency potential, acting at the circuit, rises so that the original modulation percentage is restored.

Fig. 2 illustrates an exemplified embodiment in which the need of audio-frequency transformers is eliminated. The input resistance consists here of the resistance R_3 . From a tap on the resistance R_3 by lead 20 is supplied to the diode 1 at the same time the audio frequency as well as the direct current voltage resulting from the rectification of the audio frequency to the resistance R_1 . By shifting the tap or slider along R_3 it is possible to adjust working conditions to any desired modulation percentage. The load resistance R_2 is high compared with the resistance R_3 to the end that, when making adjustments, the direct-current voltage may change as little as feasible, and that the modulating audio frequency may not be distorted.

Fig. 3 shows in what way the modulation percentage m is changed upon a variation of the plate direct current voltage U_a of tube V, without application of the idea underlying the invention (Graph 1) and with application thereof (Graph 2). The curvature of the graphs is due to limited measuring accuracy. It will be noticed that the degree of modulation is maintained extremely constant and stable by applying the invention.

What is claimed is:

1. In a modulation system of the absorption type, a high frequency circuit wherein radio frequency voltages to be modulated appear, a rectifier coupled to said high frequency circuit to rectify said radio frequency voltage and derive a current the intensity of which corresponds to the amplitude of said voltage, a source of modulating potentials, a second rectifier coupled to said source of modulating potentials to rectify said modulating potentials to derive a second current the intensity of which corresponds to the ampli-

tude of said modulating potentials, means for opposing said currents to derive resultant current when the said two currents are unequal, the direction of flow of which depends on the relative intensities of said first two currents, means for impressing said resultant current on said first rectifier to control the bias thereof, and a connection between said source of modulating potentials and said first rectifier for controlling the instantaneous current therethrough in accordance with the modulating potentials.

2. In a modulation system, a parallel tuned circuit wherein high frequency wave energy to be modulated is caused to flow, a first rectifier and a first resistance in series connected in shunt to said parallel tuned circuit whereby high frequency energy is rectified and current flows in said resistance of an intensity corresponding to the amplitude of said high frequency energy, a source of modulating potentials, a second rectifier and a second resistance in a series circuit excited by modulating potentials from said source whereby said modulating potentials are rectified and direct current flows in said second resistance of an intensity corresponding to the amplitude of said modulating potentials, means for connecting said second resistance in parallel with said first resistance whereby said currents are opposed and when unequal provide a resultant potential, the polarity of which depends on which current is greater, said potential being applied to said first rectifier as a biasing potential, and means for impressing modulating potentials on one of said resistances.

3. In a modulation system, a parallel tuned circuit wherein wave energy of carrier wave frequency is caused to flow, a rectifier and a load resistance for said rectifier in series connected in shunt to said parallel tuned circuit, a source of modulating potentials, means for impressing said modulating potentials on said load resistance, and means for rectifying said modulating potentials to derive direct current voltage which corresponds to the envelope of the modulating potentials and impressing the same on said resistance to thereby stabilize the percentage modulation in the presence of fluctuations in the wave energy of carrier wave frequency.
